CLAIM

I claim the ornamental design for the stuffed toy animal, as shown and described.

DESCRIPTION

FIG. 1 shows a front, right, and top perspective view of a stuffed toy animal in accordance with the present invention; FIG. 2 shows a front elevational view of the stuffed toy animal of FIG. 1;

FIG. 3 shows a rear elevational view of the stuffed toy animal of FIG. 1;

FIG. 4 shows a left side elevational view of the stuffed toy animal of FIG. 1;

FIG. 5 shows a right side elevational view of the stuffed toy animal of FIG. 1;

FIG. 6 shows a top plan view of the stuffed toy animal of FIG. 1; and,

FIG. 7 shows a bottom view of the stuffed toy animal of FIG. 1.

The dotted lines on the hat and the broken lines on the back represent stitching.
